**BRACKET ATTACHABLE TO A RECEPTACLE
AND TO A WATER CONDUIT**Francis M. Moore, 11 Patricia Road,
Danvers, Mass. 01923

Filed Nov. 19, 1973, Ser. No. 417,149

Term of patent 14 years

Int. Cl. D8—08

U.S. Cl. D8—246

FIG. 1

FIG. 2

FIG. 3

FIG. 1 is a bottom plan view of a bracket attachable to a receptacle and to a water conduit showing my new design.

FIG. 2 is a side elevational view of my said bracket, and FIG. 3 is a top plan view of said bracket.

I claim:

The ornamental design for a bracket attachable to a receptacle and to a water conduit, as shown.
